ARM GARMENT

Jeanne M. Allaway, La Grange, Ill. (½ Davis, McCaleb and Lucas, 230 W. Monroe St., Suite 2040, Chicago, Ill. 60606)

Filed July 29, 1974, Ser. No. 492,549

Term of patent 14 years

Int. Cl. D2—07

U.S. Cl. D2—452

FIG. 1 is a front and top perspective view of an arm garment showing my new design;

FIG. 2 is a rear and top perspective view; and

FIG. 3 is a bottom plan view.

I claim:

The ornamental design for an arm garment, substantially as shown and described.
